Primary Examiner — Philip S Hyder*Assistant Examiner* — Darlington Ly(74) *Attorney, Agent, or Firm* — Dorsey & Whitney LLP**CLAIM**

The ornamental design for an automobile grill, as shown and described.

DESCRIPTION

FIG. 1 shows a front isometric view of an automobile grill; FIG. 2 shows an elevation view of the automobile grill of FIG. 1; and, FIG. 3 shows an enlarged, front isometric view of the automobile grill of FIG. 1. The broken lines in FIGS. 1, 2, and 3 represent the environment and portions of the structure of the automobile grill that form no part of the claimed invention.
